(57) **CLAIM**

The ornamental design for a display screen or portion thereof with graphical user interface as shown and described.

DESCRIPTION

FIG. 1 is a front view of a first image in a sequence for a display screen or portion thereof with graphical user interface showing our new design; and,

FIG. 2 is a front view of a second image thereof.

The appearance of the figures sequentially transitions between FIGS. 1-2. The process or period in which one image transitions to another forms no part of the claimed design. The dot-dash broken lines illustrate a display screen or portion thereof and form no part of the claimed design. The even-dash broken lines illustrate portions of the graphi-
